CLAIM

The ornamental design for a auxiliary top for a work-bench, as shown and described.

DESCRIPTION

FIG. 1 is a rear elevational view of an auxiliary top for a workbench showing my new design;

FIG. 2 is a front elevational view thereof;

FIG. 3 is a bottom plan view thereof;

FIG. 4 is a left side elevational view, the right side being a mirror image thereof;

FIG. 5 is a top plan view thereof; and

FIG. 6 is a perspective view thereof on a reduced scale.

FIG. 1

FIG. 2

FIG. 3

FIG. 4

FIG. 5

FIG. 6
